UNITED STATES PATENT OFFICE.

ROBERT B. GREENWAY, OF SAN BERNARDINO, CALIFORNIA.

DRAINING DEVICE FOR CYLINDERS.

1,287,969.

Specification of Letters Patent. Patented Dec. 17, 1918.

Application filed September 7, 1916, Serial No. 118,850. Renewed October 8, 1918. Serial No. 257,410.

To all whom it may concern:

Be it known that I, ROBERT B. GREENWAY, a citizen of the United States, residing at San Bernardino, in the county of San Bernardino and State of California, have invented a certain new and useful Improvement in Draining Devices for Cylinders, of which the following is a specification.

My invention relates to improvements in 10 draining devices for cylinders.

While it is adapted for many uses. It is particularly well adapted for use in connection with an air pump carried by a locomotive employed for pumping up a pressure for 15 the air brake system.

One of the objects of my invention is to provide novel means by which a cylinder may be drained automatically when not under pressure.

20 My invention provides further novel means by which the cylinder may be drained when under pressure and without necessitating the engineer getting out of his cab for this purpose.

25 Another object of my invention is to provide a valve mechanism of novel construction adapted to be used in connection with my improved draining system.

Other novel features of my invention are 30 hereinafter fully described and claimed.

In the accompanying drawing which illustrates the preferred embodiment of my invention,

35 Figure 1 is a side elevation showing my improvement applied to a locomotive boiler and air pump.

Fig. 2 is a view, enlarged, in vertical section, of the valve mechanism and some of the parts connected therewith.

40 Fig. 3 is a horizontal section on the line 3—3 of Fig. 2.

Fig. 4 is a horizontal section on the line 4—4 of Fig. 2.

Similar reference characters designate 45 similar parts in the different views.

1 designates the pumping cylinder of an air pump carried by a locomotive, and provided with a drainage opening 2 with which communicates one arm of a U-shaped conductor 3, the other arm of which communicates with an inlet 5 in the lower end of a vertical valve casing 6, which is provided with a lateral outlet 7 which communicates with the atmosphere.

55 Intermediate of the inlet 5 and outlet 7 is a valve seat 8, against which is adapted to

bear a vertical movable self-opening valve 9 having an upwardly extending stem 10 which is smaller than and extends through a vertical hole 11 in the upper end of the casing 6.

The upper end of the casing 6 is provided with external screw-threads fitted in the internally screw-threaded lower end of a vertical cylinder 12, the upper end of which is connected by a steam conductor 13 with the steam boiler 14 of the locomotive.

The conductor 13 includes the shut-off valve 15.

The conductor 3 includes in its lowermost 70 transverse portion a drain cock 16.

Reciprocative in the cylinder 12 is a piston 17 adapted to be forced, by steam pressure from the conductor 13 exerted against its upper end, downwardly into contact with the upper end of the stem 10, so as to force the valve 9 from the seat 8 against the fluid pressure which forces the said valve against the seat. In order that this may be accomplished, the area subject to steam pressure at 80 the upper end of the piston 17 is greater than the area of the valve subject to an upward pressure by the steam thereunder. The piston 17, cylinder 12, conductor 13, and shut-off valve 15 comprise manually controlled fluid actuated means for forcing the valve 9 from its seat.

For normally forcing the piston 17 upwardly away from the valve stem 10, I provide yielding means comprising a vertical 90 coil spring 18 in the cylinder 12, the upper end of the spring bearing against the lower end of the piston, and the lower end of the spring resting on the casing 6.

In order that the conductor 13 may be 95 drained, the piston 17 is provided with a longitudinal hole 19, which is closed at its lower end by the stem 10, when the piston moves down and strikes said stem.

For preventing the valve 9 from closing 100 the passage 5, when the valve is in the open position, the bottom of the casing, which comprises preferably a screw plug 20, is provided on its upper side with one or more pins 21, adapted to support the valve 9 in an elevated position above the passage 5.

In the automatic operation of my invention, the drain cock 16 is normally closed, so when the cylinder 1 is not under pressure, water will pass therefrom through the conductor 3 and the inlet 5 into the casing 6 and around the valve 9, which is resting by

gravity on the pins 21, and thence out of the casing through the outlet 7. To prevent freezing, the cock 16 may be opened at any time so as to drain the conductor 3 and 5 casing 6.

When there is pressure in the cylinder 1, this pressure will be communicated to the casing 6 and will cause the valve 9 to be closed against the seat 8. The engineer may 10 drain the cylinder when the pressure is on without getting out of his cab, by opening the shut-off valve 15. The steam from the boiler will then pass through the conductor 13 into the cylinder 12 and will force the 15 piston 17 downwardly, against the pressure of the spring 18 until the piston comes in contact with the valve stem 10, at which time the latter will close the opening 19, and the steam pressure above the piston will 20 force the valve 9 downwardly from the seat 8, thereby permitting the pressure in the cylinder 1 to force water out of the conductor 3 and casing 6 in the manner already described.

25 After the engineer has closed the valve 15, the steam pressure above the piston 17 will be relieved by leakage between the piston 17 and the valve stem 10 through the opening 19, whereby the pressure in the 30 lower part of the conductor 13 will be relieved through the valve 15.

The spring 18 will then force the piston 17 to its uppermost position, shown in Fig. 2, and the pressure below the valve 9 will 35 force it to its seat 8. At this time the stem 10 will be separated from the piston 17, and the cylinder 12 and lower portion of the conductor 13 will drain into the casing 6 through the opening 11, and thence out of 40 the casing 6 by way of the outlet 7, the opening 19 permitting water to pass from above the piston 17 into the cylinder 12 below the piston.

I do not limit my invention to the structure shown and described, as modifications, 45 within the scope of the appended claims, may be made without departing from the spirit of my invention.

What I claim is:—

50 1. In draining devices for cylinders, a cylinder having a drain opening, a discharge conductor having a valve casing provided with a valve seat and a discharge opening at the outer side of said seat, a self-opening valve adapted to be forced by pressure in said conductor against said seat, a

boiler, a cylinder, a steam pipe having shut-off means and connected with the last named cylinder, a piston in said last named cylinder movable against said valve by pressure in the cylinder for opening said valve and having a longitudinal opening adapted to be closed by said valve, and yielding means for normally forcing said piston away from said valve. 60 65

2. In draining devices for cylinders, a cylinder having a drain opening, a U-shaped conductor having one arm connected with said opening, the other arm having a valve seat and a discharge opening above said 70 seat, both arms being vertical, a vertically movable self-opening valve movable upwardly by pressure in said conductor against said seat, a second cylinder, a boiler, a conductor having shut off means and connecting said boiler and said second cylinder, a piston in said second cylinder adapted to be forced by pressure therein against and to open said valve against pressure in said conductor first named and having a longitudinal opening adapted to be closed by said 75 valve, and a spring for normally forcing the piston away from said valve. 80

3. In draining devices for cylinders, a valve casing having an inlet and an outlet 85 and a valve seat between said inlet and said outlet, a self-opening valve in said casing adapted to be moved by pressure therein against said seat, a cylinder having an inlet for fluid, a piston in said cylinder movable 90 by pressure therein against said valve for opening the valve against pressure in said casing and having a longitudinal opening adapted to be closed by said valve, and yielding means for normally forcing the piston 95 away from said valve. 95

4. In draining devices for cylinders, a valve casing having an inlet and an outlet and a valve seat between the inlet and the outlet, a self-opening valve in said casing movable 100 by pressure therein against said seat, a cylinder having an inlet for fluid, a piston in said cylinder movable by pressure therein against said valve for opening the latter, the piston having a longitudinal opening adapted to 105 be closed by said valve, and a spring for normally forcing said piston away from said valve.

In testimony whereof I have signed my name to this specification.

ROBERT B. GREENWAY.
